UNITED STATES PATENT OFFICE.

JOSEPH L. FIRM, OF BERWYN, ILLINOIS, ASSIGNOR TO THE GOSS PRINTING PRESS COMPANY, OF CHICAGO, ILLINOIS, A CORPORATION OF ILLINOIS.

PRINTING-PRESS.

1,086,908.

Specification of Letters Patent.

Patented Feb. 10, 1914.

Application filed April 5, 1911. Serial No. 619,022.

To all whom it may concern:

Be it known that I, JOSEPH L. FIRM, a citizen of the United States, and a resident of Berwyn, county of Cook, and State of Illinois, have invented certain new and useful Improvements in Printing-Presses, of which the following is a specification.

My invention relates to improvements in printing presses of the web type and has for its object the provision of an improved press of this character which shall be of simple construction and efficiency in operation and capable of producing a paper or book having a large number of sheets.

The invention consists in the combination and arrangement of parts hereinafter described and claimed.

The invention will be best understood by reference to the accompanying drawings forming a part of this specification and in which,

Figure 1 is a diagrammatic sectional view illustrating a printing press embodying my invention, Fig. 2 a partial top plan view of the printing press with certain parts broken away and the webs removed, Fig. 3 a section of the press taken on substantially line $x-x$ of Fig. 1, Fig. 4 a section taken substantially on line $y-y$ of Fig. 1, and Fig. 5 is a large sectional view of the transverse folding and delivery mechanism employed in the press.

The preferred form of construction as illustrated in the drawings comprises two sets of printing mechanisms arranged side by side each of which consists of four similar sets of mechanisms arranged one above the other and each adapted to deliver a web fully printed on both sides. Each of these printing mechanisms comprises form cylinders 1 and 2 provided respectively with suitable inking mechanisms 3 and 4 and suitable impression cylinders 5 and 6 all arranged to print a web 7 on both sides. The specific form of each of these printing mechanisms is fully described in my co-pending application filed on March 8th, 1911, Serial No. 613,105 and needs no further description here.

Each of the webs 7 in each set of mechanisms passes through suitable guide rollers to a suitable slitting mechanism 8, where said webs are associated together and slit longitudinally into two separate webs 7'. Inasmuch as there are two sets of printing mechanisms this will produce 4 sets of webs

7' and each set will consist of four separate webs. The webs 7' may be passed downwardly over a V-former to a suitable cutting, folding and delivering mechanism 10, the webs 7' from one set of printing mechanism 60 being delivered at the top of said cutting, folding and delivering mechanism and the other at the bottom as indicated in Fig. 3. The completed papers are delivered to delivery belts 11. This mechanism is fully described in my prior Patent No. 868,854 granted on October 22, 1907, and needs no further description here. I might add, however that, if desired, the webs 7' from one set of printing mechanisms shown to 70 the left of Fig. 3 may be passed to cutting, folding and delivering mechanism 10 associated with the webs delivered from the other set of printing webs and thus delivered to the same delivery belt 11'. Said arrangement is indicated in dotted lines in Fig. 3, the portion of the web 7' diverted to accomplish this being marked 7''.

Another slitting mechanism 12 is arranged between the sets of printing mechanisms 80 in front of cutting, folding and delivering mechanism 10, and suitable V-formers 13 lead therefrom to a different form of cutting, folding and delivering mechanism so that the sets of webs from the printing 85 mechanisms may be passed to this other form of cutting, folding and delivering mechanism. In this case each of the V-formers 13 leads to longitudinally folding rollers 14 from which the sets of webs 7' pass 90 to pairs of cutting cylinders 15 and 16 and 17 and 18 arranged to receive the sets of webs as indicated in Fig. 4. These cutting cylinders are of a well known type and need no further description here. Suitable guide 95 rollers 19 and 20 are provided for directing the sets of webs to the cutting cylinders and rigid guides 21 and 22 are arranged between said guide rollers and said cylinders to insure accurate guiding of the sets of 100 webs thereto. The cutting cylinders are arranged in oppositely disposed pairs as shown to associate the sheets cut from the sets of webs. These sheets pass from the cutting cylinder through a rigid guide 23 105 to a suitable transverse folding and delivering mechanism 24 which delivers the folded sheets to a delivery belt 25. This transverse folding and delivering mechanism is fully disclosed in my prior Patent 110

Number 671,993 granted April 16th, 1901, and needs no further description here. It might be stated, however, that in this instance the cylinder 26 is made adjustable toward and away from cylinder 24 to permit of adjustments for different number of sheets, and it might also be added that if desired, this mechanism may be arranged to receive and associate two discharges of sheets from the cutting cylinders before itself discharging, so that in this way two sets of sheets from the cutting cylinders may be associated together and transversely folded. By this arrangement, it will be observed that a 64 sheet or a 128 sheet paper or book may be printed and delivered at a single operation and that additional matter to be associated with this may be readily and efficiently produced by employing the cutting, folding and delivering mechanism 10.

While I have illustrated and described the full construction for carrying my invention into effect, this is capable of variation and modification without departing from the spirit of my invention. I, therefore, do not wish to be limited to the exact details of construction as set forth, but desire to avail myself of such variations and modifications as fall within the scope of the appended claims.

Having described my invention what I claim as new and desire to secure by Letters Patent is:

1. In a printing press a series of superimposed web perfecting cylinder mechanisms with means for feeding a web to each of said mechanisms, in combination with a second series of similar super-imposed mechanisms arranged in parallel relation therewith, web slitting means in front of

each of said series, means for feeding the webs from each mechanism in the respective series to the respective slitting means, a pair of V-formers in advance of each of said slitting means, a second pair of V-formers in advance of each of the first mentioned V-formers, and cutting and folding mechanisms arranged between the corresponding pairs of V-formers associated with each of said series and adapted to feed the associated webs from each, substantially as described.

2. In a printing press a series of superimposed, web perfecting cylinder mechanisms with means for feeding a web to each of said mechanisms, in combination with a second series of similar super-imposed mechanisms arranged in parallel relation therewith, web slitting means in front of each of said series, means for feeding the webs from each mechanism in the respective series to the respective slitting means, a pair of V-formers in advance of each of said slitting means, a pair of cutting mechanisms arranged between the lower end of said pairs of V-formers, means for guiding the webs from said pairs of formers to the respective cutting mechanisms, means for associating the severed portions of the web passing from said cutting mechanisms, and means for folding said associated severed portions, substantially as described.

In testimony whereof I have signed my name to this specification in the presence of two subscribing witnesses.

JOSEPH L. FIRM.
